SELF-ALIGNING IDLER FOR CONVEYER BELTS

Eugene E. Landahl, Detroit, Mich.

Application October 7, 1944, Serial No. 557,609

2 Claims. (Cl. 198—202)

This invention relates to idlers of the type adapted for use in the support of conveyer belts, and is more particularly concerned with idlers of the self-aligning type which compensate automatically to properly center the belt on the idler rolls under operating conditions which tend to cause the associated conveyer belt to move laterally to positions out of proper registration with the idler rolls.

When the advancing run of an elongated conveyer belt is improperly loaded, that is, with the material being conveyed by the belt disposed so that it does not occupy a balanced centralized position on the belt, there is a tendency for the belt to move laterally of its supporting idler rolls. Efforts have been made to overcome this tendency by mounting the rolls on a supporting frame which, at its center, is pivoted for swinging movement about a substantially vertical axis carried by the stationary base structure of the idler assembly. However, with this construction, experience has disclosed that the pivoted roll-supporting frame possesses such inertia moments which following deflection thereof from its normal operating position, renders it difficult to properly realign itself with other cooperating idlers and for this reason the same have not proved to be altogether satisfactory in practice.

Therefore, it is a primary object of the present invention to provide an improved conveyer belt-supporting idler assembly having a center roll turnable about a fixed horizontal axis and a pair of side rolls turnable about axes disposed in acute angular relationship to the axis of the center roll and in diverging relation with respect thereto, and wherein provision is made for supporting the side rolls to admit of bodily turning movement thereof about vertical axes, whereby under conditions of improper belt loading, the side rolls automatically assume positions compensating for lateral misalignment of the belt and its subsequent restoration to positions properly centered on the idler construction.

It is another object of the invention to provide a self-aligning and antifriction idler assembly wherein the side rolls are supported for rotation on upwardly inclined spindles, the latter terminating at the inner end of each of the side rolls in downwardly and vertically directed extensions which are rotatably received in vertically disposed bearings carried by the base frame of the assembly.

It is a further object of the invention to provide a belt idler assembly in which the lower ends of the vertically journaled extensions of the side

roll spindles are provided with cranks which are pivotally united at their outer ends with a link member, so that deflection of one of the side rolls from its normal operating position will cause corresponding and compensating movement on the part of the other side roll.

For a further understanding of the invention, reference is to be had to the following description and the accompanying drawing, wherein:

10 Fig. 1 is a top plan view of an idler assembly for conveyer belts formed in accordance with the present invention;

Fig. 2 is a front elevational view thereof;

15 Fig. 3 is a vertical transverse sectional view taken through the idler assembly on the plane indicated by the line 3—3 of Fig. 2;

Fig. 4 is a vertical longitudinal sectional view taken through one of the end rolls showing its supporting spindle;

20 Fig. 5 is a similar view taken through the middle roll.

Referring more particularly to the drawing, the numeral 10 designates the base frame of my improved idler assembly. Mounted on the upper 25 surface of the frame is a pair of spaced bearing brackets 11, these brackets being formed with bearings to receive the ends of a horizontally disposed shaft 12 on which is rotatably mounted a middle belt-supporting roll or pulley 13, anti-friction thrust-receiving bearings 14 being disposed between the shaft 12 and the end walls 15 of said roll.

At each end of the middle roll, the assembly 30 provides a pair of angularly disposed side rolls 16. These rolls are rotatably supported on spindles 17, the longitudinal axes of the latter being upwardly inclined and acutely angular to the horizontally disposed longitudinal axis of the middle roll, so that a conveyer belt 18 supported by and 35 passing over the upper surfaces of said rolls will possess transversely a trough-like configuration for the support and retention of loose materials carried by the belt.

At the inner ends of the side rolls 16, the supporting spindles thereof terminate in downwardly directed substantially vertically disposed journaling extensions 19. These extensions are rotatably received in bearing openings 20 provided in the brackets 11, so that said extensions may turn 40 about substantially vertical axes, turning with them the side rolls 16. In order that turning movement of one of the side rolls will impart corresponding turning movement to the other side roll, the lower ends of the extensions 19 terminate in diametrically reduced studs 21 which pass

through openings provided in the base frame 10. The lower ends of these studs have fixed thereto crank arms 22, and the outer ends of these crank arms have pivoted thereto as at 23 the ends of a connecting link 24.

By the use of an idler so constructed, it will be seen that when the belt tends to run toward one side of the assembly, a condition due to a number of causes, but most often produced by the improper loading of material on narrow width belts particularly, the roll 16 on the side toward which the belt tends to move will turn slightly from its normal operating position taking with it the opposite side roll with which it is connected and thereby causing the belt to be restored automatically to its normal centered position of operation. This arrangement is decidedly effective since the end or side rolls are of light construction and by being pivoted for turning movement about an arc of short radius, the same will readily change positions in response to forces applied thereto by the conveyor belt. The middle roll or pulley, having a stationary base, functions as a stabilizer, thus enabling the whole idler assembly to operate efficiently in securing proper belt performance. Preferably, when viewed in plan, the axes of the side or end roll 16 is slightly angular to the axis of the middle roll, as indicated by dotted lines in Fig. 1. By so disposing the axes of the rolls 16, their arrangement is rendered more sensitive to operating conditions, causing the end rolls to rotate truly, somewhat after the manner of the mounting of the front wheels of automotive vehicles wherein a slight "toe-in" is provided.

While I have described what I consider to be a preferred embodiment of my invention, nevertheless, it will be understood that the same is subject to certain variation or modification without departure from the spirit and scope of the following claims.

I claim:

1. An idler assembly for the support of conveyor belts comprising a base, spaced bearing brackets carried by said base, a middle roll, means carried by said brackets supporting said middle roll for rotation about a substantially horizontal axis, an upwardly inclined side roll arranged at each end of said middle roll, spindles for the rotatable support of said side rolls, said spindles terminating at the inner ends of said side rolls in downwardly directed substantially vertically disposed extensions, the latter being turnably positioned in openings provided therefor in said brackets and disposed between the adjacent ends of the middle and side rolls, crank arms joined with the lower ends of said extensions, and a link member having its ends pivotally connected with the outer ends of said crank arms.
2. An idler assembly for the support of conveyor belts comprising a base, spaced bearing brackets carried by said base, a middle roll, means carried by said brackets supporting said middle roll for rotation about a substantially horizontal axis, an upwardly inclined side roll arranged at each end of said middle roll, spindles for the rotatable support of said side rolls, said spindles terminating at the inner ends of said side rolls in downwardly directed substantially vertically disposed extensions, the latter being turnably positioned in openings provided therefor in said brackets, said extensions occupying positions between the outer ends of the middle roll and the inner ends of the side rolls, crank arms joined with the lower ends of said extensions, and a link member having its ends pivotally connected with the outer ends of said crank arms, the longitudinal axes of said side rolls when the latter are viewed in plan being disposed in acute angular relationship to the longitudinal axis of said middle roll.

EUGENE E. LANDAHL.
